(57) **CLAIM**

The ornamental design for a bathroom play station, as shown and described.

DESCRIPTION

FIG. 1 is a right front perspective view of a bathroom play station showing our new design.

FIG. 2 is a left front perspective view of FIG. 1.

FIG. 3 is a front elevational view of FIG. 1.

FIG. 4 is a rear elevational view of FIG. 1.

FIG. 5 is a left side elevational view of FIG. 1.

FIG. 6 is a right side elevational view of FIG. 1.

FIG. 7 is a top plan view of FIG. 1; and,

FIG. 8 is a bottom plan view of FIG. 1.

The broken lines shown in the drawings are for illustrating the environment for the bathroom play station and form no part of the claimed design. The shading lines shown in the drawings represent the three dimensional contour of the design and are not intended to indicate surface decoration.
